(57) **CLAIM**

The ornamental design for a combination water gun and self-propelled toy, as shown and described.

DESCRIPTION

FIG. 1 is a perspective view, taken slightly from above, of a combination water gun and self-propelled toy showing my new design;

FIG. 2 is a right side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a perspective view, taken slightly from above, of the combination water gun and self-propelled toy in an upside-down position relative to the position shown in FIG. 1;

FIG. 8 is a right side elevation view thereof;

FIG. 9 is a rear elevation view thereof;

FIG. 10 is a front elevation view thereof;

FIG. 11 is a top plan view thereof; and,

FIG. 12 is a bottom plan view thereof.
